UNITED STATES PATENT OFFICE.

WEBSTER L. MARBLE, OF GLADSTONE, MICHIGAN.

RECOIL-PAD FOR FIREARMS.

1,349,779.

Specification of Letters Patent. Patented Aug. 17, 1920.

Application filed November 4, 1919. Serial No. 335,590.

To all whom it may concern:

Be it known that I, WEBSTER L. MARBLE, a citizen of the United States, residing at Gladstone, in the county of Delta and State of Michigan, have invented certain new and useful Improvements in Recoil-Pads for Firearms, of which the following is a specification.

This invention has for its objects, first, 10 the provision of a rubber cushion or recoil pad for firearms which is of improved construction whereby, while readily responding to the recoil and serving as a check or shock absorber, it will have such stability that its 15 walls will not flatten or collapse too suddenly at the instant of recoil; second, to provide a novel recoil pad comprising a rubber cushion or shock absorber and a pair of metal clenching plates, the whole being a self-contained 20 device adapted for attachment as such to the stock of the fire arm, or for removal therefrom, without necessitating the use of cement or the employment of two or more kinds of rubber cemented together; third, 25 to provide a novel rubber recoil pad of such form that it will have extreme resiliency, without requiring the use of springs, so that it will adequately take up the recoil when the fire arm is discharged and yet will not 30 flatten or collapse too suddenly at the instant of recoil, combined with a pair of improved metal clenching plates serving as a base by which the pad may be readily attached as a unitary structure to the stock of a fire arm, or removed therefrom, either by the direct 35 fastening of the device by screws, or, by detachable connecting means such as I have provided, for instance, in my application Serial No. 287,736, filed April 5, 1919.

40 In my invention, instead of using cement to attach the pad to the gun stock, or molding a metal attaching frame in the rubber forming the cushion, or forming the pad with a cap to fit over the stock, or employing 45 inflatable sacks or chambers, a pair of plates is applied to the rubber cushion in an improved manner so as to form a unitary structure therewith which is self-contained and attachable as such to the stock of the fire 50 arm, either by directly screwing the plate to the stock, or, providing special attaching means for that purpose as proposed, for instance, in my application Serial No. 287,736.

The rubber pad is formed for the applica- 55 tion of the pair of plates thereto. The rub-

ber pad is of novel form, provided with ribs or bars whose edges are normally spaced from the attaching plates, thereby obtaining the novel effect of stability, without the possibility of flattening or collapsing suddenly 60 at the instant of recoil and giving the pad both pneumatic and cushion features, while permitting it to be constructed of a minimum amount of material having ample strength and durability. The spacing of the 65 edges of the ribs from the plates permits the cushioning movement or compression to occur, with ready yielding of the ribs, and yet the extent of compression is limited so that the pad will not suddenly collapse. 70

The clenching plates are formed and correlated in an improved manner, affording a rigid and stiff base for the pad and an adequate clenching action on the latter.

The invention is susceptible of modification and the disclosure thereof is to be considered as illustrative, instead of restrictive, of the scope thereof. 75

In the accompanying drawings,

Figure 1 is a vertical section of a portion 80 of a fire arm stock to which my recoil pad is applied by attaching means such as set forth in my application Serial No. 287,736;

Fig. 2, a detail face view of a butt plate such as disclosed in my aforesaid application and which may be used for the attachment of the recoil pad; 85

Fig. 3, a detail face view of the pad shown in Fig. 1, showing the form of the outermost plate; 90

Fig. 4, a section on line 4—4 of Fig. 1, showing the inner clenching plates;

Fig. 5, a detail face view of the rubber recoil pad before the clenching plates are applied thereto; 95

Figs. 6 and 7, detail face views of the clenching plates before they are applied to the rubber pad of Fig. 5;

Fig. 8, a vertical section showing another form of the invention wherein the recoil pad 100 is adapted to be directly screwed to the fire arm stock without requiring the use of special attaching means, such as shown in Fig. 1;

Fig. 9, a detail face view of the recoil pad 105 of Fig. 8, the clenching plates being in position;

Fig. 10, a section on line 10—10 of Fig.

8; and

Figs. 11 and 12, detail face views of the 110

clenching plates of the form of the invention shown in Figs. 8, 9 and 10, before said plates have been clenched.

A portion of the stock of a fire arm is shown at 1. My present invention can be embodied in a form adapted for attachment in a special manner, as shown in Fig. 1, for instance, by the use of means such as set forth in my application Serial No. 287,736, thereby permitting quick and easy substitution of a recoil pad of a given thickness for a pad of any other thickness, or, the pad may be directly screwed to the stock 1 as shown in Fig. 8. Whichever manner of attachment is employed, the principle of the invention remains the same.

Referring first to Figs. 1 and 3, the special means for attachment of the pad comprises a butt plate 2 having a dove-tailed rib 3 and secured to the stock 1 by screws 4. A spring 5 secured to the plate 2 at the point 6 is adapted to lock the recoil pad after it has been engaged with the rib 3.

The attaching device just described is shown in my application Serial No. 287,736.

My present invention comprises three parts, a recoil pad 7 and inner and outer clenching plates 8 and 9. The plate 8 is provided with slots 10 and an elliptical flange 11 offset from the face of the plate. The plate 9 has a longitudinally extending dove-tailed channel 12 terminating in a flange or stop 13, and lateral flanges or beads 14 which are turned down at 15. The plate 9 is provided with struck up tongues 16 which are originally in the form shown in Fig. 6 and are passed through the slots 10 and clenched down as shown at 17 to clamp the plates 8 and 9 together in engagement with the recoil pad 7 as shown in Figs 1 to 4. Another tongue 18 which is bent at right angles and extends through the center slot 10, serves as an abutment for the locking spring 5. The spring 5 is adapted to snap into the slot 10 when the pad is in position. To attach the recoil pad, in the before mentioned form of the invention, the channel 12 is made to receive the end of the rib 3 and the pad is then slid into position with the shoulder 3^a abutting the flange or stop 13, whereupon the spring 5 snaps into the center slot 10.

This particular fastening means for a pad for a fire arm stock, I do not claim herein as the present invention is not limited to this manner of attaching the clenching plates 8 and 9, and the pad 7, to the stock 1.

Referring to Fig. 5, the recoil pad 7 is of soft rubber, of a general outline adapting it to serve the purpose for which it is intended. Said pad is hollow and open at its inner face as shown at 19, said opening being flanked by grooves 20 which receive the turned down portion 15 of the flange 14. The pad is also cut away at 21 to receive the

end portion of the plate 9 and it is cut away at 22 to receive the opposite end of said plate below the stop 13. The plate 9 is provided with struck up clenching prongs 23 which penetrate the web at the cut out portion 22. These prongs may bear against the elliptical flange or bead 11 or stop short of it.

The hollow pad 7 is provided with a plurality of relatively thin parallel partitions, 75 ribs or bars 24 whose free edges 25 are spaced from the plate 8, thus permitting the clenching plates to move a given distance before the plate 8 comes in engagement with said partitions or ribs. When the fire arm 80 is discharged the recoil causes the aforesaid relative movement, which absorbs the shock and when the partitions or ribs engage the plate 8, cushioning boxes are provided between the parts so that the effect is a combined cushion and pneumatic action. The space between the edges of the partitions and the plate 8 permits instant response at the time of discharge, the cushioning effect being thereafter more gradually exerted 85 when the contact is effected. An opening 26 extending through the pad 7 is in line with the spring 5 so that by the insertion of a nail, pencil, or other suitable device, the spring 5 may be depressed to permit the pad 95 to be removed.

It will be observed that the plates 8 and 9 have their clenching flanges or parts 11 and 14 disposed on opposite sides of the flange or part 27 of the pad 7, leaving the 100 major portion of the pad 7 free to flex as before described.

Referring to the form shown in Figs. 8 to 12, the form of the inner clenching plate 8 is the same as previously described, but 105 there are three, instead of two, tongues 16 to clamp the plates 8 and 9 together; also the plates have openings 28 and 29 for the reception of screws 30 which are intended to pass into the stock 1 in the screw holes 110 occupied by the screws which hold the ordinary butt plate, the latter having first been removed. The special fastening means previously described for use in attaching the recoil pad to the stock, is not used in this 115 form of the invention. Consequently, it is unnecessary to form the outer clenching plate 9 with a channel and stops. The outer plate 9 is of substantially the same appearance as the inner plate 8. The pad 7 is provided with openings 31 which are in line with the openings 28 and 29.

The action of the pad in the construction shown in Figs. 8 to 12 is the same as previously described.

It will be observed that my improved pad comprises a soft rubber cushion and a pair of clenching plates which afford a base for securing it to the stock and that the use of cement is entirely eliminated; furthermore, 130

it is unnecessary to provide any special means for connecting the recoil pad to the stock although such special means may be used if desired, as shown in the form of

5 the invention disclosed in Figs. 1 to 7.

What I claim is:

1. A unitary recoil pad for firearms comprising a hollow, flexible pad proper having an open face, and a pair of plates secured 10 together and covering said open face, said plates having their marginal portions permanently clenched to said pad and being positioned and adapted for connecting the pad to the firearm butt.
- 15 2. A recoil pad for firearms comprising a pad proper which has an open face and a flange or bead arranged around said open face, and a pair of connected attaching plates covering said open face and having 20 marginal portions which are clenched against opposing sides of said flange or bead, said plates being positioned and adapted for connecting the pad to the firearm butt.
- 25 3. A unitary recoil pad for fire arms comprising a hollow elastic pad proper which has internal ribs, bars or partitions said pad and its ribs being free to flex and an attaching plate secured to the pad proper, said 30 plate being positioned and adapted for connecting the pad to the firearm butt.
- 35 4. A recoil pad for fire arms comprising a hollow pad proper which has freely projecting internal ribs, bars or partitions, and an attaching plate secured to the pad proper, said ribs, bars or partitions having free outer edges disconnected from said plate and adapted to bear on said plate.
- 40 5. A recoil pad for fire arms comprising a hollow pad proper which has internal ribs, bars or partitions, and an attaching plate secured to the pad proper, said ribs, bars or

partitions having their free edges normally separated, or spaced from the attaching plate and adapted to bear against the said 45 plate.

6. A unitary recoil pad for fire arms comprising a hollow elastic pad proper provided with freely projecting flexible members in its interior, said pad and flexible 50 members being free to flex, and an attaching plate secured to said pad which is positioned and adapted for connecting the pad to the firearm butt.

7. A unitary recoil pad for fire arms comprising a hollow elastic pad proper provided with spaced parallel freely projecting flexible ribs, bars or partitions in its interior, said pad and flexible partitions being free to 60 flex, and an attaching plate secured to said pad which is positioned and adapted for connecting the pad to the firearm butt.

8. A recoil pad for fire arms comprising a hollow elastic pad proper provided with spaced parallel freely projecting flexible 65 ribs, bars or partitions in its interior, and an attaching plate secured to the pad proper and covering the said ribs, bars or partitions, said plate being positioned and adapted for connecting the pad to the firearm 70 butt.

9. A unitary recoil pad for fire arms comprising a hollow elastic pad proper provided with spaced parallel freely projecting flexible ribs, bars or partitions in its interior, 75 said pad and flexible partitions being free to flex, and an attaching plate secured to the pad proper and covering the said ribs, bars or partitions having their edges normally spaced from 80 said covering plate and adapted to engage therewith when the fire arm is discharged.

In testimony whereof I affix my signature.
WEBSTER L. MARBLE.
